UNITED STATES PATENT OFFICE.

MADISON T. B. WASHINGTON, OF NEW YORK, N. Y., ASSIGNOR OF ONE-FIFTH TO
JAMES W. WITHERSPOON, OF NEW YORK, N. Y.

MECHANICAL MOTOR.

1,109,380.

Specification of Letters Patent.

Patented Sept. 1, 1914.

Application filed December 22, 1910, Serial No. 598,767. Renewed February 3, 1914. Serial No. 816,333.

To all whom it may concern:

Be it known that I, MADISON T. B. WASHINGTON, a citizen of the United States, residing at New York, in the county and State 5 of New York, have invented new and useful Improvements in Mechanical Motors, of which the following is a specification.

This invention relates to mechanical motors or devices for transforming rotary into 10 oscillatory movement, or vice versa, and consists of the peculiar mechanism hereinafter fully described and claimed, and illustrated in the accompanying drawings, in which—

Figure 1 is an end elevation of the device 15 in a preferred embodiment, partly in section on the line 1—1 of Fig. 2, and Fig. 2 is a similar view taken at right angles to that of Fig. 1, the section being on the line 2—2 of Fig. 1.

Throughout the following description and 20 on the several figures of the drawings similar parts are referred to by like reference characters.

At 10 is indicated any suitable form of 25 support or frame, upon which is journaled at 11 a counter shaft 12. On this shaft may be secured any suitable means, such as a gear wheel 13, a pulley 14, or a sprocket wheel 15, through any of which power may 30 be conveyed to any desired place for use. A fly wheel 16 also may be employed on said shaft.

M is a motor or prime mover of any desired nature or power, from which the device 35 may be driven. Said motor is shown as including a shaft 17 provided with a crank disk 18 of any suitable size or heft and having a wrist pin 19 operating, as shown, in a slot 20 in a pendulum 21, pivotally suspended 40 from a support 22 near the upper part of the frame 10. It will be understood, however, that the disk might be grooved to accommodate a pin projecting from the pendulum, without departing from the spirit of 45 the invention.

A pair of bell cranks 23 are pivoted at 24 on the frame on opposite sides and in substantially the plane of oscillation of the pendulum, against the toes 25 of which the 50 pendulum alternately and successively impinges, causing the bell cranks to oscillate on said pivots 24. Each bell crank 23 is so designed and counterpoised, as by a

weight 26, a coiled spring 27, or a leaf spring 28, as to always insure that its toe 25 55 will contact the adjacent edge of the pendulum. Each bell crank, furthermore, is provided with an operating pawl 29 arranged to engage and drive a ratchet wheel 30 on the aforesaid shaft 12, whereby the alternate 60 and successive reciprocations of the pawls will produce a continuous rotation of said shaft. Each pawl is maintained in proper operative relation to its ratchet wheel by means of a spring 31, connected as shown to 65 the hub of the bell crank and to the pawl. Upon rotation of the shaft 17 and disk 18 through the prime mover M the wrist pin 19 will cause the pendulum 21 to oscillate, which operation of the pendulum will cause 70 the bell cranks 23 to swing on their pivots in alternation and rotate the ratchet wheels 30 through the pawls 29. The fly wheel will cause a substantially steady rotation of the driven shaft 12, and by virtue of the intermediate mechanism described and illustrated 75 such rotation of the shaft 12 will be much more powerful than that of the shaft 17 though at a slower angular velocity.

Having thus described my invention, what 80 I claim as new and desire to protect by Letters Patent of the United States is:

1. The combination of a prime mover including a rotary shaft, a disk, a pendulum adapted to oscillate adjacent said disk, a pin 85 and slot connection between said disk and the pendulum whereby the latter may be operated from the prime mover, a pair of bell cranks pivoted on opposite sides of the pendulum and in substantially the plane of its 90 oscillation and adapted to be operated in alternation by the pendulum, a counter shaft, and means between the bell cranks and the counter shaft whereby the latter is rotated from the bell cranks, substantially as set 95 forth.

2. The combination of a prime mover having a rotary element and a wrist pin, a pendulum mounted to oscillate in a plane adjacent to and transverse of said rotary element and having a slot in which said pin operates, a pair of bell cranks pivoted substantially in said plane on opposite sides of the pendulum and adapted to be oscillated in alternation thereby, counterpoise means to 100 maintain the bell cranks in contact with the 105

edges of the pendulum, a counter shaft, and pawl and ratchet devices between the bell cranks and the counter shaft, whereby the latter is given a constant rotation from the oscillation of the bell cranks, substantially as set forth.

In testimony whereof I have hereunto af-

fixed my signature in the presence of two witnesses.

MADISON T. B. WASHINGTON.

Witnesses:

G. L. BEELER,

THOMAS DURANT.
